VEGETABLE PEELER

William E. Urschel, Valparaiso, Ind.

Application May 21, 1934, Serial No. 726,693

14 Claims. (Cl. 146—49)

- The present invention relates to a vegetable peeler and particularly to that type of machine having roll peeling members having abrasive thereon.
- 5 The objects of the invention include:
A new peeling machine of improved construction having few movable and stationary parts thereby decreasing wear, simplifying construction, and increasing its efficiency.
- 10 A simplified silent drive for such a machine that is totally enclosed yet easily accessible.
An improved support for the peeling rolls facilitating their removal from the device for the purpose of replacement or otherwise.
- 15 An improved and simplified method of oscillating peeling rolls in such a machine.
A suitable motor support provided with adjustable means for varying the tension of the drive belts.
- 20 New and improved peeling rolls of simplified construction.
A new discharge spout provided with suitable drain.
- 25 These objects, and such other objects as may hereinafter appear, are obtained by the novel construction, unique arrangement, and improved combination of elements shown in the embodiment of the invention illustrated in the accompanying four sheets of drawings hereby made a part of this specification, and in which:
- 30 Figure 1 is a front elevation of a device embodying the preferred form of the present invention;
Figure 2 is a right-end elevation of the device with respect to Figure 1;
Figure 3 is a left-end elevation of the device with respect to Figure 1;
Figure 4 is a fragmentary view of the device taken from the front with portions of the hopper and housing broken away to display the driving mechanism and peeling rollers, other parts being in section;
- 35 Figure 5 is a detail displaying an end view of the peeling roller drive and oscillating mechanism;
Figure 6 is a transverse section of the machine taken on line 6—6 of Figure 1 looking in the direction of the arrows;
- 40 Figure 7 is a transverse section of the machine taken on line 7—7 of Figure 1 looking in the direction of the arrows;
Figure 8 is an enlarged sectional view of a peeling member taken longitudinally thereof;
- 45 Figure 9 is an end view of the holders at the drive ends of the peeling roller units;
- Figure 10 is a side elevation of the holder shown in Figure 9 also illustrating a fragmentary section of the drive end of a peeler roll;
- 50 Figure 11 is a side elevation in detail of the holder at the opposite end of the peeler roller illustrated in Figure 10, the peeler roll being shown in fragmentary section;
- 55 Figure 12 is an end elevation of the roller holder shown in Figure 11;
- Figure 13 is a perspective of a casting supporting one end of the peeling roller units and the roller oscillating mechanism; and
- 60 Figure 14 is a side elevation of the peeler roller oscillating mechanism with the gear shown in fragmentary section.
- 65 Like reference characters are used in the drawings and throughout the following description for designating similar parts of the device.
- 70 Support for the whole apparatus is upon a frame indicated generally by the reference character 20 and illustrated in Figures 1, 2 and 3. Legs 21 at the right end of the frame are connected to the longitudinal side members 22 and 23 (Figures 5, 6 and 7) of a housing designated 24 and are held in spaced lateral relation by the 75 straps 25, 26 and 27 (Figure 2).
- 75 The left end of frame 20 includes legs 28 held in spaced relation at their lower ends by a strap 29. The two pairs of legs 21 and 28 are additionally braced at their lower ends by rods 30 80 which are encased in the tubular spacing members 31 (Figure 1). Nuts 32 threaded upon the ends of tie rods 30 draw the legs together against the ends of the spacing members 31. At the left end of housing 24 is a casting 33 or otherwise 85 formed member forming a part of such end and anchoring the upper ends of the legs 28.
- 90 The peeling of vegetables is accomplished in the present device by the rotary and oscillatory action of abrasive cylinders 34 illustrated in Figures 4, 6, 7, 8, 10 and 11. If desired, the peripheral portions 34a (Figure 8) of the cylinders 34 may comprise porcelain in which a fine abrasive 35 is baked or attached thereto in any other convenient method.
- 95 Cylinders 34 may be a single or continuous tube of porcelain or they may be made up of several tubular sections 34a held securely on a tube 36 by collar 37 in threaded relation with said tube (Figure 8) and the collar 38 held in position by 100 the groove 39. Collar 38 may be pressed in groove 39, welded in position on the tubes 36 or secured in any other conventional manner.
- 105 Washers 40 made up of resilient material may be disposed between the porcelain members 34a 105

and collars 37 and 38 to distribute pressure evenly over the ends of such members and for their protection.

Positioned at each end of the tube 36 are identical roller bearings 41 held in place by identical collars 43 and lubricant seals 44 pressed or otherwise secured in the said tube 36. This duplication of parts and machining operations greatly reduces the manufacturing costs in respect to the machine. Lubricant seals 44 not only prevent the escape of lubricant but also protect bearings 41 from dirt and the like.

At the right end of the tubes 36 (Figure 8) are cone-shaped washers 45 pressed or otherwise secured in grooves 46 forming a V-shaped pulley designated 47 providing means for rotating the peeling rollers 34 about shaft 42. Two cylinders 34 forming a unit have pulleys 47 disposed in position shown in Figure 8, while the two cylinders making up the other unit have their pulley in the position assumed by the cone-shaped washers 45a indicated by dotted lines in Figure 8 or in the position shown in Figure 10, designated 47a.

25 A disc 48 (Figure 8) pressed or otherwise secured in groove 49 serves to protect the pulleys 47 and 47a from water constantly being sprayed upon the vegetables during the peeling operation. Disc 48 being thin and rotating at high speed acts as a "slinger" throwing off water at a tangent to its periphery.

Squared sections 50 at the right end of shaft 42 (Figure 8) are adapted to fit into the complementary square apertures 51 in the roller holder 52 (Figures 9 and 10) where they are secured by washers 53 and nuts 54, 55, and 56 (Figures 5, 8 and 10). The ends of shafts 42 also fit into the circular apertures 57 in the holders 52 to insure rigidity (Figure 9). The arcuate hooded section 40 58 (Figures 9 and 10) on the extended portion of the roller holder 52 prevents water slung from disc 48 from being thrown upwardly into the drive mechanism.

The squared sections 60 on the opposite ends 45 of shafts 42 just described are adapted to fit in the complementary square apertures 61 in roller holder 62 (Figures 11 and 12) where they are secured by washers 63 and nuts 64. The circular ends of shafts 42 also fit in the circular apertures 50 65 of holders 62 providing additional rigidity.

55 Roller holders 62 are supported for oscillative movement upon studs 66 (Figure 3) pinned or otherwise secured in the end casting 33 and inserted in the circular aperture 66a of said holder 62 (Figure 12). Holders 52 are each supported upon a shaft 67 (Figure 5) for oscillative movement therewith, said shaft being pinned or otherwise secured in the circular aperture 68 of said 60 holders 52.

60 Shaft 67 is mounted for oscillative movement in the lower end of support 69 (Figure 5). The uppermost portion of support 69 is bolted to the face of the T-shaped projections 70 (Figure 13) of an end casting 71 by bolts 72. End casting 65 71 is riveted or in some other conventional manner secured to member 109 (Figure 4).

70 Rigidly fixed in the cylindrical projection 74 of casting 71 (Figure 13) is a stud 73 upon which there is rotatively mounted a spur gear 75 (Figure 14) held in position upon said stud by a washer 76, pin 77 and a shoulder formed at the face of projection 74.

75 Journal box 78 (Figures 4 and 13) is secured to projection 74 of casting 71 by the arm 79. Spur

gear 80, (Figure 4) has an extended solid hub (not shown) which is journalled in the box 78. V-pulley 106 is pinned or otherwise secured to the extremity of the above mentioned extended hub of gear 80.

Incorporated with the extended hub of gear 75 (Figure 14) is an eccentric 81 upon which rides the strap 82 held in position by the shoulder 83 and the plate 84 secured by bolts 85.

Integral with the eccentric strap 82 is the connecting arm 84 (Figures 4, 5 and 14) whose lower extremity is pivotally connected to the most rearwardly pair of peeling rollers by the stud-like projection 85 on the nut 54 (Figure 8) which fits in the complementary circular aperture 86a in arm 15 84.

Depending pivotally from the strap 82 is a connecting rod 86 (Figures 4, 5 and 14) held in position within the circular aperture 87 of said strap 82 by pin 88. The lower extremity of rod 86 is 20 pivotally mounted in the circular aperture 89 in the nut 55 (Figure 10) which is mounted on the shaft 42 of the forwardmost pair of peeling cylinders 34 in the device. From Figure 5, it can readily be seen that the rotation of the eccentric 25 81 by the movement of gear 75 causes an oscillative movement in the two pairs of peeling cylinders 34 by means of the two connecting members 84 and 86.

30 A base plate 90 (Figures 2 and 4) for mounting an electric motor 91 is hinged upon the rod 92. Rod 92 is secured in circular apertures 93 in leg 21 (Figure 4) and in casting 71 at 94 (Figure 5) and held against longitudinal displacement by the pins 95 and 96. The motor 91 is attached to the hinge base plate 90 by the bolts 97 (Figures 1 and 2). Keyed to the motor shaft 98 (Figure 5) is a double groove V-belt pulley 127 which drives the V-belts 99 and 100, the main drive for the 35 device.

A guard 101 (Figure 4) encloses the parts of the two V-belts 99 and 100 exposed above housing 24 as a precaution for the safety of the operator. Although guard 101 encloses the V-belts 99 and 100, it has been hinged on rod 92 in such manner 45 as to allow it to be swung in the clear when belts are replaced.

To compensate for any elongation of the V-belts 99 and 100, and insure proper tension in said belts an adjustment means has been provided. This adjustment means consists of a thumbscrew 102 (Figure 1) in threaded relation with a nut 103 welded or otherwise secured to the base plate 90. Manipulation of the thumbscrew 102 which bears upon shelf-like portion 104 of 50 the longitudinal side member 22 (Figure 5) raises or lowers the motor shaft 98 due to the hinged action of base plate 90 on rod 92, thus varying the tension in belts 99 and 100. Thumbscrew 102 may be locked in any position by means of 55 the nut 105.

A portion of the housing 24 consists of a hopper 107 having front and back sides 22 and 23 (Figure 6) in common with the left end of the housing, and an end wall 108 (Figure 4) depending downwardly into the housing. From Figure 6 it will be seen that the lower edge of end wall member 108 contains juxtaposed arcuate indented sections 109 cut upon a radius corresponding substantially to that of the arcuate 70 sections of the roller holders 62, the faces of which are alined with and complete the end wall of hopper 107 and housing 24. Similarly, at the opposite end of hopper 107 (Figure 7), the wall member 109 contains indented arcuate sec- 75

tions 110 whose radius corresponds with that of the arcuate hood section 58 of roller holder 52, (Figure 10), the face of which is also in alignment with and completes the said wall 109. This arrangement permits oscillation of the peeling roller units while at the same time retaining the vegetables within the hopper.

A spray pipe 111 positioned within the hopper 107 is shown in Figures 6 and 7. The pipe enters 10 the end wall 108 through an arcuate opening and is held in position by the bolt 112 (Figure 1). The purpose of the spray pipe 111 is to supply a liquid to be sprayed over the vegetables to cleanse them while they are being peeled and to wash the 15 refuse toward and out a refuse spout 113.

A cover 114 confines the spray and particles of vegetable peelings or skins within the hopper during the peeling operation. Rivets 115 (Figure 6) serve to pintle ears 135 at the back corners of 20 the cover to the hopper end members 108 and 109.

The peeled vegetables are discharged through opening 117 (Figure 6) at the front side of the hopper 107 and guided therefrom into any suitable receptacle by the spout 118 riveted to the hopper wall about the opening. A hinged door 119 with its lower edge adapted to fit into groove 120 may be employed for closing the opening 117 during the peeling operation. Slots 121 in 25 ear-like extensions 122 of the door 119 and through which a rod 123 passes coact with such rod to form a hinged mounting for the door. Rod 123 is suitably secured to the upper end of side members of spout 118. A handle 124 riveted 30 to door 119 provides for easy manipulation thereof. A groove or trench 125 positioned laterally at the end of the spout 118 collects any liquid that might escape while the vegetables are being discharged. Liquid collected in said groove is 35 returned to the bottom of housing 24 to be discharged through spout 113 by means of duct 126.

Nut 127 containing a circular aperture 128 and in threaded relation with the inner walls of the duct 126 serves to make a liquid-tight joint between duct 126 and longitudinal side member 22.

The bottom of housing 24 forms a drain indicated generally by the reference character 128. Substantially all of the refuse which contains waste water and particles of peeling is conducted 50 away through the drain 113.

Although gear 75 and the eccentric mechanism must be withdrawn before V-belts 99 and 100 can be replaced, the replacement of said belts is a simple procedure since only pin 77 (Figure 14) 55 needs to be extracted and then the said gear and eccentric mechanism may be removed from stud 73 as a unit.

The same procedure is followed when it is desired to remove the peeling cylinder units except that the bolts 72 (Figure 5) securing the supports 69 are also removed permitting the rollers to be withdrawn from the device in a longitudinal direction.

Door 128 (Figures 2 and 4) at the right end of 60 the device disposed in grooves 129 and 130 of straps 25 and 26, provides accessibility to the drive mechanism. An upward movement of door 128 releases it and permits withdrawal from the grooves. Handle 131 has been riveted to door 70 128 to facilitate its manipulation.

Motor 91, by means of pulley 127 (Figure 5) and V belt 100 drives pulleys 47 thereby rotating the forward pair of cylinders 34. Disposed in another groove in pulley 127 is belt 99 which acts 75 upon pulleys 47a imparting rotative movement

in the rearward pair of cylinders 34. Belt 99 also drives pulley 106 which in turn drives spur gear 80 in meshing relation with gear 75. Gear 75 actuates eccentric 81, thus causing the two connecting members 84 and 86 attached to eccentric 5 strap 82 to oscillate the two pair of cylinders 34. The oscillating or rocking movement of the cylinders is about stud 66 (Figure 3) at one end of the device, and in the lower extremity of support 69 (Figure 5) at the drive end of the cylinder. 10

The rocking or oscillating movement of the cylinder which takes place at the time of their rotation constantly changes the contour of the supporting surface of the bed of cylinders, thus permitting all sides of vegetables or other articles 15 supported thereon for peeling to have their peel or skin come in contact therewith. All cylinders 34 rotate in the same direction.

Such rotative movement together with the oscillating or rocking motion of the cylinders causes 20 the whole mass of vegetables in hopper 107 to revolve slowly in a unitary mass, thus allowing each individual vegetable to come in contact with each cylinder 34. After each individual vegetable comes in contact with the last or most rearward 25 cylinder, having traversed the others in turn while progressing rearward at the bottom of the unitary mass, such vegetable is carried upwardly to the top of the mass and progresses 30 forwardly along the top of the mass until it again progresses downwardly to the bottom of the mass to be again conducted over the cylinders. This process is repeated until all of the articles are peeled. The rocking movement of the cylinders 34 more thoroughly agitates the vegetables and thus facilitates 35 more rapid peeling. The constant turbulation of the articles by the upward and downward movement of the cylinders overcomes any tendency of the vegetables to pack into a relatively stationary group. 40

Upon completion of the peeling process, door 119 is opened and the vegetables are released through opening 117 in the side of the hopper, and are guided by chute 118 into a suitable receptacle. 45

What is claimed as new and is desired to be secured by Letters Patent of the United States is:

1. In combination, two pairs of paired parallel peeling rollers forming a peeling bed, separate pivoted support means for each pair of rollers 50 eccentric to the axes of the pairs, a prime mover, means intermediate said prime mover and said rollers for rotating all of said rollers, and an eccentric connected to said pivoted support means for conjointly moving said support means to bodily shift all of said rollers to change the contour of said bed while said rollers are rotating.

2. In combination, a plurality of pairs of parallel peeling rollers, pivoted support means for each pair of rollers eccentric to the axes of the 60 pairs, a prime mover, means intermediate said prime mover and each pair of rollers for conjointly rotating all of said rollers, and an eccentric actuated by said prime mover and connected to all of said support means for oscillating all of said rollers about their supports for changing the contour of the bed of rollers while said rollers are rotating.

3. In combination, pairs of parallel peeling rollers in staggered arrangement and forming a 70 bed, a pivoted support for each pair of rollers eccentric to the axes of the pairs, a prime mover, belt means between each pair of rollers and said prime mover for driving all of said rollers in one direction, and eccentric means connected to all 75

- of said supports and driven by one of said belt means for oscillating all of said rollers for changing the contour of the bed of rollers while said rollers are rotating.
5. In a vegetable peeling machine the combination of means forming a hopper, a support associated with said hopper, a prime mover on said support, a plurality of pairs of elongated rollers rotatably and oscillatably mounted on said hopper in spaced arrangement to provide a hopper bed, means actuated by said prime mover and connected to each roller for rotating it, means forming an oscillatable mounting for each pair of rollers, a single eccentric movably mounted on said hopper, means actuated by said prime mover for operating said eccentric, and a connection from said eccentric to each oscillatable mounting for oscillating the pairs of rollers.
5. In a vegetable peeling machine the combination of means forming a hopper, a casting associated with said hopper, a prime mover associated with said hopper, a plurality of pairs of elongated rollers rotatably and oscillatably mounted on said hopper in spaced arrangement to provide a hopper bed, said casting providing a laterally extending journal outside of said hopper, a gear rotatably mounted on said journal, a pinion rotatably mounted on a journal on said casting, and having teeth meshing with the teeth 30 of said gear, a pulley for rotating said pinion, an eccentric shiftably mounted on the journal toward said gear, said prime mover having a drive shaft provided with a pair of pulleys, means forming an oscillatable mounting for each pair of rollers, a connection from said eccentric to each oscillatable mounting, a pulley for each roller, and a belt passing from one pulley of the prime mover shaft about each of the roller pulleys of one pair and a second belt passing from the other 40 pulley of said prime mover shaft about the pulleys of the other pair of rollers, one of said belts passing about the pulley of said pinion.
6. In a peeling mechanism comprising a bed of peeling rollers for supporting articles to be peeled, means for moving adjacent rollers bodily up and down to change the level of sections of the article-supporting area of the bed, and means for rotating said rollers during such movement, said rotating means comprising pulleys associated 50 with said rollers and driving belt means engaging a plurality of said pulleys.
7. In a fruit or vegetable peeler, a peeling bed comprising a plurality of parallel peeling rollers arranged in an upwardly inclined plane, means for rotating said rollers about their respective axes toward the higher side of said bed, and means for continuously moving rollers laterally into and out of the plane of said bed while rotating said rollers, said rotating means comprising 60 a driving belt engaging pulleys associated with said rollers.
8. In a peeling mechanism comprising a bed of peeling cylinders, means for moving adjacent cylinders bodily up and down to change the level 65 of sections of the article-supporting bed, and means to continually rotate said cylinders comprising a driving belt and driving pulleys, said

moving means comprising an eccentric and links reciprocated by said eccentric and associated with said cylinders.

9. In a peeling mechanism comprising a plurality of peeling members comprising a bed and rotatable about parallel horizontal axes, means for simultaneously moving all adjacent peeling members bodily in opposite directions up and down to change the level of sections of the article-supporting area of said bed, and means for 10 continuously rotating said cylinders during such motion, said means comprising a driving belt associated with a plurality of pulleys on said peeling members.

10. A peeling mechanism comprising a series 15 of paired peeling rollers, supporting means for each pair of rollers pivotal about an axis eccentric thereto, means comprising a driving belt to rotate the peeling members, and means to rock said pairs of peeling members on said pivot comprising a driven eccentric means and links reciprocated by said eccentric and associated with said support means.

11. A peeling mechanism comprising a series 20 of paired peeling rollers, supporting means for each pair of rollers pivotal about an axis eccentric thereto, means comprising a driving belt to rotate the peeling members, means to rock said pairs of peeling members on said pivot comprising a driven eccentric means, links reciprocated by said eccentric and associated with said support means, and means to position said eccentric, said links being secured to said eccentric means and being maintained in operative relation by the 30 means positioning said eccentric.

12. In a peeling mechanism, the combination 35 of a hopper, a plurality of pairs of rotatable peeling rollers, a pulley for each of said rollers, a driving belt for said rollers and associated with said pulleys whereby to drive said pulleys, and 40 eccentric means for automatically shifting each of said rollers bodily in an arcuate path having an axis between the axes of said rollers.

13. In a peeling mechanism comprising a bed 45 of adjacent paired peeling cylinders rotatable about parallel axes for supporting articles to be peeled, means for simultaneously oscillating the cylinders of each pair about an axis parallel to the cylinders to shift the position of each of the cylinders simultaneously to change the level of 50 the cylinders in the surface of said bed, and means for continuously rotating said cylinders, said means comprising pulleys associated with said cylinders and a driving belt engaging a plurality of said pulleys.

14. In a device of the character described, a bed of peeling cylinders mounted on supports for reciprocation transversely of said bed, means for continually rotating said cylinders in the same direction, and means for oscillating said cylinders 60 in their transverse path comprising a driven eccentric means and links freely positioned in said supports, the eccentric means and links being of a unitary organization whereby assembly of one member of said unit will maintain the 65 other members in operative position.

WILLIAM E. URSCHEL.
